UNITED STATES PATENT OFFICE.

WILLIAM M. BASHLIN, OF GROVE CITY, PENNSYLVANIA.

PROCESS OF REMOVING ROSIN AND TURPENTINE FROM RESINOUS WOODS.

1,136,994.

Specification of Letters Patent.

Patented Apr. 27, 1915.

Application filed May 11, 1912, Serial No. 696,747. Renewed February 10, 1915. Serial No. 7,371.

To all whom it may concern:

Be it known that I, WILLIAM M. BASHLIN, a citizen of the United States, residing at Grove City, in the county of Mercer and State of Pennsylvania, have invented new and useful Improvements in the Process of Removing Rosin and Turpentine from Resinous Woods, of which the following is a specification.

- 10 This invention relates to the process of removing turpentine and rosin from resinous woods and consists in certain improvements therein as will be hereinafter fully described and pointed out in the claims.
- 15 I have shown an apparatus for carrying out my process in an application filed by me March 29th, 1912, Serial Number 687,085. This apparatus is illustrated in the accompanying drawings and consists in an inner shell 1 which is preferably cylindrical in form and is closed at top and bottom by suitable heads 2 and 3, one of these heads, the head 2 in the present instance, being preferably provided with a dome 4 which is 20 covered by a tight-fitting lid 5, the latter being held in position by a suitable clamp 6. One side of the retort is also preferably provided with a manhole 7 which may be conveniently located toward the bottom of the 25 retort and communicates with the interior thereof. This manhole is covered by a tight-fitting lid 8 which may also be held in position by a clamp 9. The retort is practically inclosed by an outer jacket 10 which forms 30 a heating space or chamber 11 which is adapted to receive steam through a pipe 12 which may be connected to any suitable source of steam supply such, for example, as the steam pipe 13. The bottom of the retort 35 contains a support for the charge of wood and this support, according to the present invention, serves also as a filter or strainer. In the present instance, the support embodies a suitable number of superposed 40 plates 14 which are foraminous or formed with perforations 15, these perforations in the plates being preferably staggered or offset, as shown. A sheet of fabric 16 of appropriate character is preferably arranged 45 at the under side of the uppermost foraminous plate and sheets of woven wire mesh 17 are interposed between the middle and the top and bottom plates. This structure just described is suitably supported in the lower 50 portion of the retort, for example, by an internal flange or ledge 18 and the plates and

the mesh are maintained in proper spaced relation by suitable means such, for example, as the rings 19. A residuum chamber 20 is formed in the bottom of the retort below the support just described, and an outlet 21 is provided for drawing off the residuum. The residuum chamber 20 contains piping which is preferably in the form of a coil 22 having vents or orifices 23, this coil being connected by a pipe 24 to receive the steam supply pipe 13 whereby steam may be admitted to the coil 22 and this steam may be projected from the vents or orifices 23 therein through the charge support and filter. An outlet 25 also extends through the bottom or lower portion of the retort and serves to withdraw the solvent or liquid therefrom, this outlet being shown provided with a strainer head 26 and a blower 27 may be arranged 60 in co-operative relation with the strainer head, the blower being connected by a pipe 28 to the steam pipe 24 and steam may be admitted to the blower under the control of a valve 29 whereby the accumulation of any 65 substance on the strainer head tending to clog the same can be removed when necessary. The outlet pipe 25 for the solvent preferably leads to a suitable circulating pump 30 and the discharge side of this pump 70 is connected by a pipe 31 to the inlet 32 of a coil or percolator 33, the coil shown in the present instance being formed with numerous downwardly directed vents or orifices 34 through which the solvent may be 75 distributed evenly over the charge contained 80 in the retort.

That portion of the retort between the lower and upper coils 22 and 33 contains 85 means for heating the interior of a charge or body of wood contained in the retort whereby all portions of the charge may be heated uniformly by the application of heat thereto both exteriorly and interiorly. Heating means of different kinds may be 90 used for applying heat interiorly to the charge. In the present instance, an imperforate helical heating coil 35 is shown and this coil may receive steam at an appropriate temperature through the pipes 36 and 37. 95 These pipes may be conveniently connected to the steam supply pipe 13 and provided with appropriate valves 38 and 39 whereby the steam supply to the coil and consequently the heating effect or temperature 100 of the coil may be regulated as conditions may require. Means is also provided for in- 105

jecting steam in the body of the charge for the purpose of liberating the turpentine and light oils therefrom. In the present instance, a suitable number of vertical manifolds 40 are shown which are connected in the form of a frame which surrounds the coil 35, and each manifold is connected to a suitable number of steam distributing pipes 41, these pipes in the present instance radiating from the center of the retort and provided with vents or orifices 42 through which the steam is discharged and distributes uniformly within the body of the charge. The manifolds and the distributing pipes 5 may also serve as means for distributing the solvent throughout the body of the charge and to accomplish these results, a pipe 43 may be used which leads to the manifolds and this pipe is connected to and may receive steam from the supply pipe 13 under the control of a suitable valve 44, and the pipe 43 is also connected to the solvent circulating pump 30 and may receive solvent therefrom under the control of 10 a valve 45. When the valve 45 is closed and the valve 44 is opened, steam from the pipe 13 is admitted to the manifolds 40 and is discharged evenly throughout the body of the charge through the perforated distributing pipes 41. By closing the steam valve 44 and opening the valve 45, the solvent may be caused to enter the manifolds 40 and discharge directly into the mass through the distributing 15 pipes 41. A pipe 46 leads from the dome 4 and is preferably connected to a suitable vacuum pump whereby a pressure below atmospheric pressure may be maintained within the retort during the treatment of each charge. A pipe 47 also leads from the dome 20 4 and may serve to convey away and condense such gases as may accumulate in the dome. These gases may be withdrawn by any suitable exhaust device, an ejector 48 being shown in the present instance and the nozzle 25 49 thereof may receive steam from the steam pipe 13, as shown. In order to condense and thereby prevent high pressure of any gases that may accumulate in the upper portion of the retort, due to the combined action of the 30 hydrocarbons native to the wood and the hydrocarbons in the solvent, a cooling coil 50 may be used, that shown in the present instance being adapted to receive water or other cooling medium through the inlet pipe 35 51 and the water from the coil may discharge through the outlet 52. Gage glasses 53 and 54 may be provided for indicating the level of the liquid in the upper and lower 60 portions of the retort, and a safety valve 55 may be provided to prevent the development of excess pressure in the retort. Steam may also be introduced by way of the coil 33, pipe 31, valve 31^a, portion of pipe 25, valve 45, pipe 45^a, valve 44, the valve 25^a being closed. 65 In carrying out my process, I preferably

subject the chips in the retort to the following steps: The retort being filled, the chips are preferably heated although this is not absolutely essential through the heating mediums hereinbefore described, namely, the chamber 11 and coil 35. A solvent, preferably the solvent described in my application filed Nov. 10th, 1911 #659,634 may be used which solvent is made up of 80% deodorized benzin and 20% wood turpentine. With my process I maintain the level of the body of solvent at the bottom of the retort near the bottom of the chips and spray the top of the chips with the solvent allowing it to percolate down through the chips. In this way, the solvent is continuously moving taking up the rosins and oils in this movement and at the same time, the chips are not subjected to the pressure that would be incident to submerging them in the solvent. The process may be made more efficient by reducing the pressure to which the chips are subjected during this washing process by putting the retort under a vacuum through any convenient apparatus as by way of the pipe 46. Where this is done, the chips are not only free from any presence of the solvent itself but, of course, are subjected to the reduced pressure incident to the partial vacuum. At the same time, the solvent is kept in nearly as intimate a contact with the different parts of the chips as though the chips were submerged and the continued movement of the solvent carries the products from the chips with it to the bottom where it can be taken off. The gases exhausted in reducing the pressure in the retort are condensed and utilized. This process not only has the advantage of the greater efficiency as before described but it involves the use of a very small amount of solvent compared with the process where the chips are submerged. This being so, the after treatment of this solvent to take out the different products is very much simplified. In the carrying out of this process ordinarily the solvent may be circulated for some time, by way of the pipe 25, pump 30, pipe 31, 32, 33 and nozzles 34. This may be continued until the solvent has attained such richness as to interfere with its efficiency when it may be thrown off for treatment and the fresh solvent introduced. After the products have been extracted from the chips as far as can be done by the washing process heretofore described, the solvent is drawn from the retort and the chips are subjected to a current of steam.

Heretofore it has been common to subject the chips of wood in the retort to a current of steam or other heating medium directed or applied to the chips in one direction, usually from the bottom toward the top. This has been effective in taking up the light oils but has lacked effectiveness as to the

heavier oils. With my process I propose to subject the chips to currents of steam or heating medium and to reverse the direction of the movement so as to take up the lighter oils in one direction and to more readily take up the heavier oils when applied in the opposite direction.

In carrying out this process with the apparatus described, I first turn on the steam through the pipe 24, and nozzles 23 allowing the steam to pass upwardly and discharge it through the pipe 47. This flow of steam may be augmented by way of the pipe 43, distributing pipes 40 and 41 and nozzles 42. This would pick up the lighter oils. Steam may then be introduced by way of the pipe 31 and 32 and nozzles 34 discharging by way of the pipe 21. This would take up the heavier oils with greater efficiency than where the flow of steam is upwardly. With the flow of steam in either direction, the supply may be augmented by the introduction of steam by way of the pipe 43 via pipe 40, distributing pipes 41 and nozzles 42. Steam from this system will follow the direction of the discharge. After this steaming process alternated as described there ordinarily remains in the chips some material that may be saved. In order to extract this final product from the chips, I introduce to the retort preferably from the bottom a liquid heavier than the solvent and the products, preferably water, at or about a boiling temperature. This water as it rises in the retort picks up the remaining solution made up of the solvent and the products and carries them upwardly with them through the body of the chips and the richer portions of this product so picked up may be drawn off at the top of the retort by way of the pipe 33. The amount of water drawn off can be observed and the process continued until the products drawn off are practically free from the solution. The retort is then emptied, the water being drawn off to a storage for re-use so that the same water is used each time and in this way any solution that may be maintained by the water is finally reclaimed. After this the retort is discharged in the usual manner, preferably through the opening 7 and recharged.

What I claim as new is:—

1. The process of removing rosin and turpentine from resinous woods which consists in subjecting such wood to heat; extracting rosin and turpentine from the wood by the action of a percolating liquid solvent while maintaining the wood in an unsubmerged condition, the withdrawal of the solvent rich in extract, the application of steam in an upward direction to drive off the residue of

turpentine and the easily volatilized substances from the wood, the application of steam in a downward direction, the application of water at about the boiling point, and drawing off at the surface of the water the products separated from the wood by the water.

2. The process of removing rosin and turpentine from resinous woods which consists in subjecting such wood to a pressure below atmospheric pressure, extracting rosin and turpentine from the wood by the action of a percolating liquid solvent while maintaining the wood in an unsubmerged condition, the withdrawal of the solvent rich in extract, the application of steam in an upward direction to drive off the residue of turpentine and the easily volatilized substances from the wood, the application of steam in a downward direction, the application of water at about the boiling point, and drawing off at the surface of the water the products separated from the wood by the water.

3. The process of removing rosin and turpentine from resinous woods which consists in subjecting such wood to heat and a pressure below atmospheric pressure; extracting the rosin and turpentine from the wood by the action of a percolating liquid solvent while maintaining the wood in an unsubmerged condition, the withdrawal of the solvent rich in extract, the application of steam in an upward direction to drive off the residue of turpentine and the easily volatilized substances from the wood, the application of steam in a downward direction, the application of water at about the boiling point, and drawing off at the surface of the water the products separated from the wood by the water.

4. The process of removing rosin and turpentine from resinous woods which consists in subjecting the wood to a pressure below atmospheric pressure and extracting the turpentine and rosin by a percolating liquid solvent while maintaining the wood in an unsubmerged condition.

5. The process of removing rosin and turpentine from resinous woods which consists in subjecting the wood to heat at a pressure below atmospheric pressure and extracting the rosin and turpentine by a percolating liquid solvent while maintaining the wood in an unsubmerged condition.

In testimony whereof I have hereunto set my hand in the presence of two subscribing witnesses.

WILLIAM M. BASHLIN.
